JAMES HOWARD AND EDWARD TENNEY BOUSFIELD, OF BEDFORD, ENGLAND.

Letters Patent No. 90,450, dated May 25, 1869.

IMPROVEMENT IN STEAM-GENERATORS.

The Schedule referred to in these Letters Patent and making part of the same.

To all whom it may concern:

Be it known that we, JAMES HOWARD and EDWARD TENNEY BOUSFIELD, of Bedford, in the county of Bedford, England, have invented a new and improved Tubular Steam-Boiler; and we do hereby declare that the following is a full, clear, and exact description thereof, which will enable others skilled in the art to make and use the same, reference being had to the accompanying drawing, forming part of this specification, in which—

Figure 1, Sheet I, represents a side elevation of our improved tubular boiler;

Figure 2, Sheet I, is a sectional end or front view of the same;

Figure 3, Sheet I, is a plan or top view of the same;

Figure 4, Sheet II, is a front elevation, partly in section, of a modification of the same;

Figure 5, Sheet II, is a detail side view of the same;

Figure 6, Sheet II, is a detail vertical section; and

Figure 7, Sheet II, a detail end view of the same.

Similar letters of reference indicate corresponding parts.

This invention relates to improvements on the vertical tubular boiler for which we obtained Letters Patent, dated October 23, 1866, and July 9, 1867; the main object of the present invention being to facilitate the removal from such boilers of the scum that is thrown up by the water employed in certain localities, to improve the connections between the vertical and horizontal tubes composing the boiler, and also to facilitate the detachment and removal of any one or more of the vertical tubes, when required.

We have found, by experience, that some waters, under ebullition, instead of affording a calcareous or other deposit, throw up a scum, which, if allowed to accumulate, would seriously interfere with the working of the engine supplied with steam from the boiler. This is particularly observable when using water derived from, or that has passed over a shale-bed.

When constructing boilers for districts yielding water of this description, we propose to divide the vertical tubes into two lengths, and to interpose between the upper and lower lengths additional horizontal tubes, at about the level of the water-line, to the upper and lower sides of which the vertical tubes will be secured.

In Sheet I of the drawings, this arrangement is illustrated by groups of tubes in side elevation, end view, and plan view.

The vertical tubes are divided into two parts A A', by means of the horizontal tubes B, and they are connected at their lower ends by horizontal tubes C, as heretofore, and at their upper ends by a novel arrangement of zigzag steam-pipes, D D. The horizontal tubes B are placed side by side, so as to come in contact

with each other, to form a close division in the heating-chamber, they thus serving the purpose of the plates heretofore used for returning the flame and heated gases to the front of the heating-chamber, and causing them to play on the upper parts of the vertical tubes.

The ordinary water-level of the boiler will be on a level with the axes of these horizontal tubes B, and there will be fitted to the end of each a scum-pipe, through which any foreign matter which floats on the water can be cleared off at pleasure.

In manufacturing the groups of tubes, it will be convenient to cast the tube B on to the half tubes A', by laying the latter in the mould, and thus to form the junctions in the mould.

The same remark applies also to the connection of the tubes C to their respective groups of half tubes A'.

The upper halves A of the vertical tubes we propose to fix in a novel way to the horizontal tubes B.

In order to simplify and improve the connection between the vertical and horizontal tubes, which connection has heretofore been made by bolts passing through projecting lugs or flanges on the vertical tubes, and tapped into nuts inserted in recesses at the sides of the horizontal tubes, we raise on the surface of the horizontal tubes conical-screwed nozzles, and form on the ends of the vertical tubes, a corresponding internal thread, which, fitted on the nozzles, will make a water-tight joint not liable to be injuriously affected by exposure in the heating-chamber.

This arrangement applies not only where the additional horizontal tubes B are used, but also to the fitting of the undivided vertical tubes to the water-supply tubes C.

This part of our invention is illustrated in figs. 4 and 5, Sheet II, in end and side elevation, one of the vertical and horizontal tubes of the group shown in fig. 4 being in section.

These figures represent the tubes A as connected to cast-iron tubes C. In this case conical threaded nozzles E are placed in the mould, and they are thus connected to the tube C in the act of casting. When, however, the vertical tubes are to be connected to wrought-iron horizontal tubes, we prefer the arrangement shown in vertical section at fig. 6, and in end elevation at fig. 7.

The horizontal tube is flattened on its upper side, and tapped to receive double-coned nozzles F, which have screw-threads cut thereon. The one screw-thread fits into the thread cut in the horizontal tube, and the other receives the tapped end of the vertical tube A.

When it is necessary to take out, for the purpose of cleaning or otherwise, a vertical tube thus fitted, we apply heat to it externally to expand it. A convenient method is to use a heated iron ring, lowered to

that part of the tube embracing the projecting nozzle. When the tube is expanded, a suitable wrench being applied to the tube, will readily start it and disengage it from the horizontal tube. As the nozzle rises above the horizontal tube, the dirt is readily cleared from it, and the vertical tube can be replaced without the workman going into the furnace-chamber.

Still further to facilitate the removal of the vertical tubes, we propose to dispense with the horizontal steam-pipes, which we have heretofore used to take the steam from the sections of vertical tubes, and to couple together two rows or sections, by means of a zigzag arrangement of short tubular pieces terminating in the main steam-pipe.

This arrangement (see fig. 3) is composed of flanged "elbows" D D, fitted one to each vertical tube, and connected together by screw-bolts passed through the flanges and secured by nuts. The connecting-piece of any tube being released from those of the adjoining tubes, that tube can be raised vertically out of its place without interfering with the surrounding tubes.

When the vertical tubes are not divided to receive the additional horizontal tubes for collecting the scum, which arrangement is required only in certain localities, as above indicated, horizontal dividing-plates will be used, as heretofore, for returning the flame and heated gases to the front of the heating-chamber. In-

stead, however, of making them pendent from rods, or providing transverse or longitudinal bars to carry them, we propose to form the tubes with enlargements at the proper level, as shown at fig. 4, and thus to form shoulders *a a* for supporting the division-plates G.

Having thus described our invention,

What we claim as new, and desire to secure by Letters Patent, is—

1. The construction and arrangement of the vertical and horizontal tubes, and the conical-screwed nozzles E and F, substantially as described.

2. The zigzag pipes D, arranged with reference to each other, and the upper ends of the vertical tubes, substantially as set forth.

3. The combination of the supports *a*, of the tubes A, and the division-plates G, arranged with reference to the vertical pipes, substantially as herein described.

The above specification of our invention signed by us, this 2d day of February, 1869.

JAMES HOWARD.

EDWARD TENNEY BOUSFIELD.
